UNITED STATES PATENT OFFICE.

NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

PANIC-BOLT HOLDBACK.

1,207,921.

Specification of Letters Patent. Patented Dec. 12, 1916.

Application filed February 5, 1916. Serial No. 76,339.

To all whom it may concern:

Be it known that I, NORMAN B. HURD, a citizen of the United States of America, residing at New Britain, Connecticut, have 5 invented a new and useful Panic-Bolt Hold-back, of which the following is a specification.

My invention relates to a hold-back device for latch bolts, the object being to provide 10 an exceedingly simple and inexpensive hold-back construction.

Ordinarily the normal position of the latch bolt is projected. Sometimes it is desirable to have the latch retracted for a 15 period. To that end my invention contemplates providing simple means to hold back the latch for as long a period as desired.

In the drawings, Figure 1 is a front elevation showing my invention as applied to 20 a so-called "panic-bolt" lock. Fig. 2 is a rear elevation relatively enlarged of certain parts shown in Fig. 1. Fig. 3 is a similar view showing the parts in a different position. Fig. 4 is a section on the line 4-4, Fig. 2. 25 Figs. 5 and 6 illustrate details.

1 represents a bolt preferably of the ordinary spring latch type.

2 represents a latch bolt operating member 30 pivoted in a bracket 3 mounted on the face of the door. This operating member may be connected with the latch 1 in any well known manner, no invention being claimed in the particular mode of connection 35 between the operating member 2 and said latch bolt 1.

4 is an arm pivotally mounted in a bracket 5. The arm 4 swings with the latch operating member 2, being connected there- 40 to by a cross bar 6. Since the parts 2 and 4 move together as one piece, I may provide a stop or latch hold-back member in connection with either the bracket 3 or 5. In this particular instance the latch hold-back 45 is connected with the bracket 5 and comprises a barrel 7 which is mounted in the bracket 5 parallel to the pivot 4^a of the arm 4. This barrel 7 is notched in one side as shown in Figs. 4 and 5, and the hub of the 50 arm 4 projects at all times into said notch to prevent the endwise displacement and accidental disengagement of the barrel from the frame. The hub of the arm 4 likewise has a notch 8 arranged to form a locking 55 shoulder.

9 is a spring designed to normally move the arm 4 from the dotted line position Fig. 4 to the solid line position. When the arm 4 stands in the position shown in the solid lines, Figs. 1, 2 and 4, the latch 1 is projected. When, however, the arms 2 and 4 are moved into the position indicated in Fig. 3 and in dotted lines Fig. 4, the latch bolt 1 will be retracted. In this latter position the barrel 7 may be turned clockwise 60 so as to cause the shoulder 10 to engage in the notch 8 thus locking the arm 4 in the dotted line position and holding the latch bolt retracted. Any suitable means may be provided for turning the barrel bolt 7, that is to say, the said barrel bolt may have an ordinary knurled end or handle, or a simple spanner wrench 11 may be employed, the end of the barrel being provided with two recesses shown in Fig. 5 to receive such 65 a spanner.

4^b is a screw or other suitable fastening by which the hub of the arm 4 may be secured on its pivot 4^a.

12 is a friction spring which may serve 80 to hold the barrel 7 against accidental displacement when it is performing the locking or hold-back function. Any suitable equivalent means may be substituted for the specific form of spring shown. 85

It is obvious that a variety of changes and modifications may be made without departing from the spirit or scope of the invention.

What I claim is:

1. In a device of the character described, a bracket, a retracting member having a hub portion pivoted in the bracket and provided with a locking shoulder, a barrel pivoted in the bracket provided with a notch 95 freely receiving the locking shoulder on the hub in the swinging movement of said retracting member and hub and provided with a locking shoulder at one end of the notch therein adapted to be brought by the turning of the barrel into the plane of the locking shoulder on the hub, manually operable means for rotating the barrel to carry the locking shoulder thereon into the plane of the locking shoulder on the hub, 100 said barrel having a notch therein in the side opposite the locking shoulder before described and a holding spring engaged in said notch. 105

2. In a device of the character described, 110

a hollow bracket having spaced apart sides, a retracting member having a hub portion disposed between the sides of said hollow bracket and provided with a locking shoulder, a pivot engaged in the sides of said bracket and pivotally supporting the hub portion of the retracting member therein, a spring within the hollow bracket exerting its tension to swing the retracting member 10 in one direction, a barrel pivoted in the hollow bracket parallel to the pivot of the retracting member and provided with a notch in the side thereof facing the locking shoulder and freely receiving the same in the

swinging movement of the retracting member and thereby preventing relative displacement of said hub portion and barrel, said barrel having a locking shoulder at the end of the notch therein to coöperate with the locking shoulder on the hub portion and 20 means at the end of said barrel for rotating said barrel to carry the notch out of the plane of the locking shoulder on the hub and position the locking shoulder on the barrel in the plane of the locking shoulder 25 on the hub portion.

NORMAN B. HURD.
